WARHEAD INITIATION TRANSFER LINK

GOVERNMENT INTEREST

The invention described herein may be manufactured and used by or for The Government of the United States of America for governmental purposes without the payment of any royalties thereon or therefor.

BACKGROUND OF THE INVENTION

In certain weapon systems it is highly desirable to utilize a nose-fuse. In such cases, it has been the practice to denote the warhead through a booster charge, for example, in the forward end of the warhead.

However, if rear initiation of the explosive can be achieved reliably, the effectiveness of the warhead will be increased. This is true principally because the side spray fragment beam will be swept forward to a more desirable lead angle.

Passing a detonating wave through a live explosive charge without impairing the effectiveness of the warhead, on the other hand, presents a number of problems. Not the least of these problems is the packaging of the transfer link so as to forestall premature initiation of the warhead. If the warhead is initiated at some point other than the desired rear end, then the resulting fragment velocities and distribution fall short of design expectation. Even if the warhead is not initiated prema-

DETAILED DESCRIPTION OF THE INVENTION

Generally illustrate in FIG. 1 is a warhead 10 comprising an explosive 14 surrounding a case 12 having attached to its forward end a conventional fuze mechanism 16. An initiation transfer link 18 is positioned centrally of the explosive 14 to transfer an initiating shock from fuze 16 to the detonating booster 20.

For a more detailed description of the transfer link, reference is now made to FIG. 2 wherein a transfer link utilizing the steel-air energy-sink configuration is shown in some detail. The link comprises an outer tubing 22 which may be of aluminum or the like of approximately 0.375 inch outside diameter with a wall thickness of approximately 0.042 (See table 1). An inner tubing 26 is held in spaced relationship with turning 22 by means of end spacers 24. The inner tubing is preferably of a harder material such as steel and approximately 0.250 inch outside diameter with a wall thickness of 0.049 inch so as to leave a space between the two tubes of approximately 0.015 inch. A mild detonating fuze (MDF) 30 is passed through the inner tube, the inside diameter of which allows for an air space 32, and the fuze is provided with end fittings 34. The space 32 may be left filled only with air or may be filled with a low density foam type material. A number of supporting spacers 36 are placed at a one or the other or both ends of the tubes to render the fuze and the end fittings relatively immobile within the tube. The detonating fuze is preferably a five grain per foot mild detonating fuze and fitting 34 is packed with a slightly higher order explosive.

turely, the explosive may be preshocked or otherwise affected by passing a detonating wave therethrough so that it would not react completely.

According to the present invention, satisfactory transfer of detonation is achieved in two preferred ways. Namely, through the use of (1) impedance matching and (2) a steel-air energy-sink configuration.

BRIEF DESCRIPTION OF THE DRAWING

FIG. 1 is a plan view, partly in cross section, of a weapon incorporating the transfer link defining the present invention; and

FIG. 2 is a longitudinal cross-sectional view of a preferred embodiment of the transfer link.

45 The second method of rear end initiation is based on the principle of impedance mismatching (See table 2). In utilizing the impedance matching approach certain primary considerations are involved. When a shock wave crosses a material boundary, an instantaneous adjustment of shock pressure occurs. The resulting conditions, after this adjustment occurs, depend largely upon the shock impedance of the two materials. If the impedances are equal or matched, the shock will move into the new medium, its peak pressure unaltered. But, if the shock impedances and materials differ, then the energy of the shock will be divided and additional shock waves and/or rarefactions will be generated, depending on the specific case. If two materials of differing impedance (such as brass and aluminum) are used in the multilayer laminar assembly, then it is possible to generate destructive interference of these resulting waves. In crossing such an assembly the pressure behind a shock can be dropped appreciably, especially if care is taken to determine and use optimum thickness values for each layer of the material.

Brass and aluminum are chosen for initial investigation for two main reasons. Brass has a shock impedance of approximately twice that for aluminum. Both brass and aluminum could be obtained in a series of nesting-thin-walled tubing. Table 3 gives the details of construction and table 2 illustrates the column performances. Considering the tables, it is apparent that even the least effective mismatched configuration performs better than all but the very heavy steel confinement. Even so, it is not until the introduction of air spaces into the cylindrical laminates that appreciable gains are made. As noted in both tables the same slight expansion after firing was produced in experiment 5. In the case of the steel confinement, over 40 percent greater diameter was required in order to obtain the same result. The same geometry was used in experiment 6 with a two-grain per foot length of MDF and no expansion at all resulted.

From the foregoing it is obvious that I have shown two methods of constructing an initiation transfer link for use in certain types of warheads. Such initiation transfer link accomplishes the transfer of initiation from a nose located fuse to a base or rear end booster, without affecting the subsequent detonation of the high explosive charge through which it passes. Although the impedance mismatch or the steel-air energy-sink method of construction produces a workable assembly for this task, in the interest of economy and simplicity of construction, the latter construction may be considered as preferred.

All of the tubing and other materials used are commercially available and require no machining to obtain the dimensions given in the table. The thin-walled tubing used as spacers is also commercially available and obtainable in a variety of materials. The assembly may be prefabricated to slip into a central aluminum-walled core of a warhead and may be hermetically sealed if desired.

What is claimed is:

1. A warhead initiation transfer link comprising in combination:
- an explosive material and fuze means passing through said explosive material;
  - means for actuating said fuze means at one side of the explosive;
  - means situated on the other side of said explosive for detonating said explosive; and
  - said fuze being connected to said detonating means so that when said fuze is actuated a detonating shock wave is passed through the explosive to said detonating means;
  - end fittings on said fuze means and shock attenuating means surrounding said fuze means;
  - said shock attenuating means comprising inner and outer tubes of dissimilar metals.
2. The transfer link according to claim 1 wherein the fuze means is a low order explosive and the end fittings are filled with a higher order explosive.
3. The transfer link according to claim 2 wherein said tubes are separated by a cushioning airspace.
4. The transfer link according to claim 2 wherein said tubes are alternately of brass and aluminum.
5. The transfer link according to claim 2 wherein said tubes are alternately of steel and aluminum.
6. The transfer link according to claim 3 wherein said outer tube is of aluminum and said inner tube is of steel.
7. The transfer link according to claim 1 wherein said attenuating means comprises a plurality of alternate aluminum and brass tubes.
8. The transfer link according to claim 3 wherein one or more airspaces are provided between tubes.
